Application November 6, 1946, Serial No. 708,126

8 Claims. (Cl. 15—304)

1

This invention relates to a container cleaning machine, and particularly to a type thereof in which the container is cleaned by inverting and directing thereinto a stream of cleaning fluid.

In the art of filling containers, such as bottles, under highly antiseptic conditions it is often desirable to direct a stream of fluid, such as air, into the container immediately prior to filling to insure the removal therefrom of dust particles, or other foreign material, which might have become lodged therein. It is desirable that such a machine work rapidly and efficiently and with a minimum of attention from the operator.

However, in cases where there may not be more than a few hundred of such bottles handled at any given time, or where there may not be more than a few hundred bottles of a particular size and capacity handled at a given time, the expense incident to using a fully automatic machine is not justified. Even if the expense of original purchase or construction might be accepted, it is often not desirable in the case of a few hundred bottles to expend the set-up and adjustment time incident to placing a fully automatic machine into operation.

Accordingly, it is desirable to provide a machine which will be sufficiently automatic to provide substantial economy in both time and labor over hand methods of directing a stream of fluid, such as air, into a bottle and yet one which is sufficiently simple in construction that it can be readily and quickly adjusted for a given size of bottle within a substantial range and placed into operating condition with a sufficiently small expenditure of time and labor as to make its use practicable with small lots of bottles.

It is further desirable for economy and convenience that such machine be operated by the same air supply which will normally be used to clean the bottles, and thus place the machine into operating condition with a single power connection.

Accordingly, a major object of the invention is to provide a semi-automatic machine for directing a stream of cleaning fluid into a plurality of bottles.

A further object of the invention is to provide a machine as aforesaid in which the bottles will be held in an inverted position while said fluid is being directed thereinto.

A further object of the invention is to provide a machine as aforesaid which can be readily adjusted to receive bottles within a substantial range of varying sizes.

A further object of the invention is to provide

5 a machine as aforesaid in which all necessary adjustments can be quickly and accurately made, whereby the machine may be placed into operation in a minimum amount of time.

10 A further object of the invention is to provide a machine as aforesaid in which the fluid used for cleaning the bottles may also be used as a source of actuating power.

15 A further object of the invention is to provide a machine as aforesaid which will be adaptable to economical initial construction and which will be capable of economical maintenance.

20 Other objects and purposes of the invention will be apparent to persons acquainted with 15 equipment of this type upon reading of the following disclosure and inspection of the accompanying drawings.

25 In constructing a mechanism meeting the objects and purposes above set forth, there is provided in general a machine having a platform fitted with means for gripping a plurality of bottles thereon which platform is rotatable about a horizontal axis by which said bottles may be turned into an inverted position. Placed below 30 said platform is a plurality of nozzles for ejecting cleaning fluid, which nozzles are supported by a vertically reciprocable platform. This nozzle platform is so reciprocated that immediately following the inverting of said bottles the nozzles will be moved upwardly to extend into said bottles, whereupon a stream of cleaning fluid, such as compressed air, is caused to emerge from each nozzle under sufficient force to remove all dust and other foreign material from the interior of each of said bottles. All of said parts are 35 arranged in a vertical line so that a single reciprocable member will, in its upward and downward movement, cause said parts to function.

In the drawings:

40 Figure 1 represents a partially phantom, side elevation of a particular embodiment of the invention.

Figure 2 represents a partially phantom, end elevation of the invention viewed from the leftward end of the machine as it appears in Figure 1.

Figure 3 is a partially sectional elevation taken from the line III—III of Figure 1.

Figure 4 is a fragmentary section taken on the line IV—IV of Figure 3 or the line IV—IV of 50 Figure 2, said lines both defining the same cross-section.

Figure 5 is an end elevation of the driving member showing also in broken lines one position of a locking cam driver relative thereto.

Figure 6 is a side elevation of the driving mem-

2

ber viewed from the leftward side of the part as appearing in Figure 5, showing in broken lines one position of a locking cam driver relative thereto.

Figure 7 is a bottom plan view of the said driving member.

Figure 8 is an end elevation of the driving member support, as viewed from its rightward end as appearing in Figure 1.

Figure 9 is an end elevation of the end sliding plate which supports the nozzle platform, viewed from the leftward end of the machine as it appears in Figure 1.

Figure 10 is a bottom plan view of the said sliding plate.

Figure 11 is a detail of the nozzle platform operating rack.

Figure 12 is a bottom plan view of said nozzle platform operating rack.

Figure 13 is an end elevation of the member supporting the end sliding plate of the nozzle platform, as viewed from the leftward end of the machine appearing in Figure 1, and showing in broken line the partial outline of the said sliding plate in one operative position relative thereto.

Figure 14 is a detail of the bottle holding mechanism viewed from the left as appearing in Figure 2.

Figure 15 is a detail of the cam driving wheel operating mechanism, as viewed from the leftward end of the machine appearing in Figure 1, showing in broken lines the outline of the driving slide with respect to the cam driving pins carried thereby, and showing two positions of the said slide and pins with respect to the locking cam.

Figure 16 is a section taken on the line XVI—XVI of Figure 1.

Figure 17 is a section taken on the line XVII—XVII of Figure 1.

The drawings illustrated and the hereinafter appearing description describe one particular machine which embodies the principles of the invention. However, it should be understood that many of the details of this machine, particularly as to its size, the number of containers which it will handle, details of frames, bearings, gears, and similar parts may be freely and widely varied without departing from the scope of the invention. Since the particular machine here utilized for illustrative purposes has been designed for cleaning bottles intended for pharmaceutical use, terminology appropriate thereto has been used heretofore and will be employed hereinafter but such terminology will be understood as illustrative only and not limiting.

Referring now more particularly to the drawings, there is provided a frame of any convenient construction, such as angle iron, welded or bolted into position for supporting the parts hereinafter described. This frame comprises four vertical leg members, of which two are shown at 1 and 2, reinforced by suitable cross members of which one appears at 3 and provided at each end of the top with platforms 4 and 5 braced by suitable side members including those shown at 6 and 7. The space between the end platforms 4 and 5 is occupied by the rotatable container supporting platform as hereinafter described in detail.

Container supporting platform

The container supporting platform comprises parts which may arbitrarily be denoted as an upper plate 10 and a lower plate 11 connected

by end plates 12 and 13 and a center plate 14 (shown in Figure 1). Centrally located in each of said connecting plates is a bearing 15 receiving a shaft 16 (Figures 1 and 4) which shaft is supported in any convenient manner in bearings 17 and 18 mounted as required on the frame.

Along the edges of the aforementioned plates 10 and 11 of the supporting platform assembly are bolted, or otherwise suitably attached, the fastening members 19 and 19a (Figures 1 and 3). The fastening members 19 on both sides of the supporting platform are drilled to receive the adjusting studs 160. These studs are held rigidly and adjustably by means of suitable nuts 161 with respect to the fastening members 19, and are threaded through the lock nuts 162 into suitably tapped and appropriately placed openings in the guide plates 20 and 21. Thus, said plates 20 and 21 are firmly supported in operating position but may be moved toward or away from the center line of the said platform as desired by adjusting the said nuts 161. This method of support for the guide plates 20 and 21 as described is one specific embodiment but is in no way intended to be limiting.

Along the opposite edges of the plates on each side of said bottle supporting platform are located the respective gripping assemblies 22 and 23. Since these are identical, detailed description will be given only of the assembly 22 and it will be understood that the assembly 23 is a duplicate thereof.

The angle 25 constitutes a base for said assembly and extends substantially the full length of the bottle supporting platform. Affixed at convenient points to said angle are suitable bolts, one of which is shown at 26, extending through the adjacent fastening members 19a and held fixedly in place with respect thereto by the nuts 27 and 28. Said bolts are received and suitably held within corresponding openings in the base member 25, of which that shown in Figure 14 at 26a is one, by which said base member is held adjustably fixed with respect to the platform 10. Spaced along the extent of the base member 25 at convenient intervals is a plurality, here three, cam shaft supports 29, 30 and 31. Suitably supported in bearings on said cam shaft supports is the cam shaft 32 which operatively supports the locking cams 33 and 34.

Pivotedly mounted with respect to the base 25 are the clamp brackets 35 and 36, to which is affixed, as by welding or bolting, the clamp bar 37 extending the full distance which the bottles 38 are intended to occupy. Said clamp bar is preferably faced with a resilient material 39, such as sponge rubber, extending its full length for effecting the actual gripping of the bottles. As best shown in Figure 3 the assembly is so arranged that in one position of the cams the clamp is in bottle receiving position, as clamp assembly 22 in Figure 3, and in another position of the cams the clamp is in bottle engaging position, as clamp assembly 23 in Figure 3. Associated with the bottle supporting parts 20 and 21 (Figure 3) is suitable stop mechanism 146 for limiting the travel of a given group of bottles into the holding positions adjacent to said parts. This stop mechanism, designated generally by the numeral 146 in both places shown, comprises any convenient and presently known construction for the purpose but may desirably be a rod 147 headed by an enlarged end 148. It is urged out of operating position by the spring 149 and releasably held in operating position by any con-

venient catch means, not shown. The stop mechanism 146 is supported by a slide mechanism 150 in Figure 1, which is adjustable and permits the operation of said rod 147 through an elongated slot 151 in the said guide plate 20.

At the end of the cam shaft, as appearing in Figures 2, and 15, is a cam driver 40 having cut-outs 41 and 41a therein for receiving the cam driving pins 42 and 42a hereinafter described. The cam driver 40 is angularly arranged on the cam shaft with respect to the locking cams so that in the position shown in Figures 2 and 15 the cam driving pin 42 moving in a vertically upward direction will enter said cut-out 41 and cause said cam driver to rotate in a counter-clockwise direction as the same appears in said figures.

The cam driver 40a in Figure 1 associated with the bottle gripping mechanism 23 is so positioned that when the bottle holding platform rotates 180° on its axis said cam driver 40a will then take the position with respect to the cam driving pins 42 and 42a which is occupied by the cam driver 40 in Figure 2. Thus the said cam driving pins 42 and 42a will actuate whichever cam driver is in operative position with respect to them.

The nozzles and nozzle supports

Shown in Figures 1 and 17 is a nozzle supporting platform 140 of any convenient construction, here an angle iron, supporting a plurality of nozzles 141 of any conventional type, aligned in position so as to be directly under the centers of and accurately in line with the openings of said bottles when same are in their inverted position preparatory for cleaning. For the purposes of longitudinal adjustment of said nozzles along said nozzle platform 140 with respect to the openings of said inverted bottles, a suitable slot is provided in the horizontal flange of the angle iron which constitutes the nozzle platform 140. The nozzles may be constructed, as in Figure 17, so that the upper body part 141a is threadedly associated with the lower body part 141b, thereby providing a suitable means of fixing said nozzles 141, with respect to the nozzle platform 140, after a slidably adjustment has been made between said nozzles and said platform with respect to the said inverted bottles.

Suspended from the nozzle platform 140 by means of the support bars 142 and 143, of any suitable material or construction, is the exhaust tube header 44 to which are suitably attached a plurality of inlet nipples 45. These nipples on said exhaust header 44 are connected respectively to the outlet nipples 48 of the said nozzles 141 by means of suitably flexible conduits 46 which are limited in their construction only by the fluid which they are to conduct and the distance they are to conduct it. Although the said nozzles 141 may be of any convenient and conventional type, they are shown here, as comprised of a head 49, suitably recessed to receive the bottle being cleaned, to which head is suitably secured the upper end of a tube 49a, which is in turn slidably held at its lower end by the upper body part 141a. A spring, sleeved about said tube 49a, is held under compression by bearing at its upper end against the lower side of the nozzle head and at its lower end against the top of the upper body part. The tube 49a is flanged at its lower end where it protrudes through the lower side of the upper body part thus preventing the said tube 49a from being

urged out of its slidable association with said upper body part due to the compression of the spring. The upper body part 141a is threadedly attached to the lower body part 141b in such a manner that a chamber 48a is provided in the lower body part.

One end of one of a plurality of suitable flexible conduits 61 is received through a suitable opening into the said chamber 48a where it is associated with the discharge tube 50, and rigidly attached thereto, which tube extends upwardly and coaxially through the tube 49a and the nozzle head 49, and protrudes beyond said head to such an extent that it will extend substantially within the bottle being cleaned thereby. The inside diameter of the tube 49a is sufficiently larger than the outside diameter of the tube 50 to permit the free passage of the cleaning fluid as it is exhausted from the bottle. The flexible conduits 61 are attached at their other extremities to the inlet manifold 60 by means of a plurality of nipples suitably fixed thereto. Said manifold is fixed in position with respect to the nozzle platform by means of any suitable support member 60a.

The cleaning fluid, as air under pressure, is released to the inlet manifold by means of a valve mechanism, 180 in Figure 3, when the rod 181 is depressed by the trigger 182 which is in turn urged by the lever 183 pivotally mounted on the pin 184. The end 185 of the lever 183 is depressed when the end 186 of said lever is urged upwardly by the shaft 100 which is designed to rise with the nozzle platform 140. Upward motion of the nozzle holding platform causes the tubes 50 to enter the mouths of the bottles and also causes the actuation of the valve mechanism as above described, thereby releasing at a predetermined time a flow of cleaning fluid into the manifold 60, through the conduit 61 and thence out through said tubes 50 into the bottles. The air is exhausted through the head 49, the tube 49a, and chamber 48a where it leaves the nozzle by means of the nipple 48 and then flows through the conduit 46 where it is collected from all nozzles by the exhaust header 44. The exhausted air is removed from the header through the outlet 47 which may be connected to a suitable exhaust system or which may discharge the air freely at this point.

The said nozzle supporting platform 140 is supported by the connecting members 55 and 56 which are affixed to the extremities of the said nozzle platform 140 and are in turn supported by vertically sliding plates 57 and 58 (Figures 1, 3 and 16) hereinafter described in more detail.

The one sliding member 58 and its associated parts on the leftward end of the machine as viewed in Figure 1 are mirror images of the sliding member 57 and its associated parts on the other or rightward end of the machine as viewed in Figure 1. Therefore, detailed description will be given only of the sliding member 58 and its associated parts on the leftward end of the machine, except where reference to parts on the rightward end is made for the sake of clarity. Such treatment will sufficiently disclose the construction and operation of member 57 and its associated parts.

The said sliding member 58 comprises, as shown in Figures 9 and 10, a rectangularly shaped part substantially wider than thick. Through said plate are a pair of slots 62 and 63 which are parallel with each other and of sufficient width to receive the hereinafter mentioned

shafts 110 and 100, respectively. Affixed into said plate member 58 on one side thereof is a nozzle adjusting rack 64, the teeth of which are positioned with respect to the slot 63 to be engaged by the teeth of a pinion supported on a shaft extending through said slot. Mounted on said sliding plate 58 is a nozzle reciprocating rack 65 (Figures 9 to 12) mounting a bearing 66 for the support of a shaft 100 hereinafter mentioned, having rack teeth 67 positioned with respect to the slot 62 so that said teeth may be engaged by the teeth of a pinion 111 supported on a shaft 110 extending through said slot 62, and having a recessed portion 68 receiving the head of a bolt 69 extending through said nozzle reciprocating rack and said slot, and held by suitable nuts 69a for supporting said nozzle reciprocating rack in sliding relationship with said vertically sliding plate 58. Said vertically sliding plate 58 is, as best shown in Figure 16, mounted onto an inner frame plate 70 shown in detail in Figure 13, and held slidably with respect thereto by spacer members 71 and 72 as shown supporting the retaining and guiding members 73 and 74 in Figure 16. Said inner frame plate is suitably mounted onto the general frame of the machine, said plate has an opening 171 therein for clearing the nut 69 and nozzle adjusting rack 64, which extend therethrough. Located adjacent said opening 171 and in position to be aligned with the slot 62 is an opening surrounded by a bearing 173 for receiving and supporting the shaft 110 as hereinafter described.

Placed oppositely to the frame member 70 is a corresponding member 80 (Figures 8 and 16) having an opening 81 therethrough for the passage of the driving connection 90 hereinafter described. An opening receiving the bearing 82 is provided through said member 80 for the end support of the shaft 110 hereinafter described. The driving slide 89 (Figure 16) is positioned against said frame member 80 and held slidably with respect thereto by the spacers 84 and 85 cooperating with the slide retaining members 86 and 87.

The slide member (Figures 5, 6 and 7) comprises a vertical driving slide part 89 having a driving flange 90 affixed as by welding to its lower end and extending out through the opening 81 as shown in Figures 1 and 16. A vertically aligned slot 91 is provided therein for the passing of the hereinafter described shaft 110. The rack elements 92 and 93 are provided on either side of said slot in a position that their teeth will mesh with the teeth of the pinion 112 supported on said shaft 110. The rack element 94 is near the upper end of said driving slide 89. The pins 42 and 42a previously described in connection particularly with Figures 2 and 15 are adjustably positioned near the top of said slide and at suitable points from the top of said slide, respectively. While these pins may be mounted in any one of several ways, it will be found effective, referring to the upper pin 42 for example, to mount said pin 42 in a block 95 which is held in adjustable relationship with the slide part 89 by means of the screw element 96, which is in turn supported by the block elements 97 and 98, rigidly mounted on the said slide part 89. Thus said pin may be adjusted to the right or left as appearing in Figure 5 and held in such adjusted position by a set screw 99. The pin 42a is mounted onto the driving slide 89 in the same manner and is similarly adjustable.

Extending parallel to the general axis of the

machine is the nozzle platform assembly, supporting shaft 100, which shaft is held at its one end in the nozzle reciprocating rack 65 by means of the bearing 66, shown in Figure 9. Similar parts are provided at the other end of said shaft 100 for similarly supporting said other end. A pinion 101 (Figure 1) is mounted on said shaft 100 immediately inside the sliding plate 58 for cooperation with the nozzle adjusting rack 64 which is mounted on said sliding plate 58 as in Figure 9, and a similar pinion 102 is on the other end of this shaft for cooperation with a similar nozzle adjusting rack associated therewith. A suitable operating handle 103 is operatively associated with said shaft 100 for manual rotation thereof by which the nozzle supporting frame, through the action of said pinions on the rack 64, thereby on the sliding plate 58 and their counterpart at the other end of the machine, is caused to move upwardly or downwardly as desired with respect to the rack 65.

The operating shaft 110, Figure 1, is parallel to the adjusting shaft 100 and is supported, as shown in Figures 4 and 16, in the bearing 82 of the end plate 80, and in a corresponding bearing in a corresponding plate at the opposite end of the machine. Said shaft extends through the slot 91 in the slide 89, as well as through the slot 62 in the supporting plate 58, both thereof being at the leftward end of the machine as appearing in Figure 1. Said shaft 110 also extends through a corresponding slot in a plate at the other end of the machine corresponding to the plate 58. Pinions 111 and 112 are mounted between the driving slide 89 and sliding plate 58 on said shaft 110 and are rotatable therewith. The pinion 111 is placed next to sliding plate 58 for cooperation with the teeth 67 of the rack 65, whereby rotation of said shaft will cause the rack 65 and supporting plate 58 to move vertically with respect to the axis of said shaft 110 and hence with respect to the general frame of the machine.

Similarly a pinion 115 is mounted between the end plate 13 of the bottle platform and the outside frame member 80 on the shaft 16 in Figure 4 for rotation therewith and cooperates with the rack 94 in Figure 5 by which, when the said rack is moved upwardly, the shaft 16 is caused to rotate in one direction and as the rack moves downwardly the shaft 16 is caused to rotate in the opposite direction.

Fixed at the leftward end of the machine as appearing in Figure 1, and preferably supported on the end of the machine by the plate 80, is the driving cylinder 120. Figure 2 illustrates a phantom view of one possible position and arrangement of the driving cylinder 120 and piston rod 121 with the latter connected in some suitable manner to the flange 90 of the driving member 89. This may comprise any conventional air cylinder reciprocably operating a suitable piston whose connected piston rod 121 is operatively connected to the driving flange 90. The cylinder 120 is supplied with any convenient source of operating fluid under pressure, preferably air, in order that the same source may, if convenient, be used as a supply to the cleaning fluid nozzles 141. Said fluid is supplied to the cylinder 120 through a suitable valve controlled by the handle 122. This valve is of any convenient, conventional construction, having one position by which the supply of air to the cylinder is prevented, one position by which the air will be permitted to drive the piston in one di-

rection within the cylinder, and another position by which the air will be permitted to drive the piston in the other direction within the cylinder.

Operation

In operating the above described device, a quantity of bottles to be cleaned is placed upon the feeding table 4. The operator then moves sufficient of them onto the upper side, or plate, of the bottle supporting platform to fill same and adjusts the stop mechanism 146 appropriately to insure that the bottles will be longitudinally aligned with the fluid ejecting nozzles, which are in turn adjusted by any convenient means as heretofore described for individual alignment with respective bottle tops. One such adjustment will, of course, be sufficient for all subsequent operations with a given size of bottle.

Actuation of the crank 103 will, by rotating the shaft 100 and pinions 101 and 102 mounted thereon, effect a movement of the rack 64 and its counterpart at the opposite end of the machine which racks are attached respectively to the sliding plates 58 and 57, thereby adjusting the nozzle platform 140, hence the nozzles 141, upwardly or downwardly with respect to the bottle supporting platform mechanism. Thus, when any group of bottles is revolved into its downward, inverted position, adequate clearance will be provided between said nozzles and said bottles during the revolving operation. However, such clearance must be held to a minimum to insure a positive contact between the nozzle heads 49 and the open ends of the said bottles when said nozzles have been raised into cleaning position. The appropriate clearance and subsequent adjustment required may be either predetermined or determined by placing one or more bottles within the clamping mechanism on the inverted side of the bottle supporting platform. In either case, however, the final adjustment of said nozzle platform will be effected by means of the handle 103.

After the above described adjustment has been made, a group of bottles are moved onto the upper plate 10 of the bottle platform and the valve control handle 122 is manually actuated in such a manner as to cause the piston rod 121 to move upwardly from a position as shown in Figure 1. Such upward motion is translated, through the flange 90 which is suitably attached both to the operating end of the piston rod and the lower end of the driving slide 89, into an upward motion of the said driving slide 89. Hence there is effected an upward motion of the pins 42 and 42a. As said pin 42 moves upwardly, it will first engage the opening 41 in the cam driver 40, causing it to rotate counter-clockwise as appearing in Figure 15 and thus move the clamp member 22 into clamping position onto said bottles.

Before the rotation of said cam driving wheel 40 and its resultant effects are completed, the upward movement of the driving member 89 has caused the engagement of the rack 92, mounted thereon along the slot 91 therein, with the pinion 112. Inasmuch as the said pinion 112, as well as the pinion 111, are suitably mounted on the shaft 110 as shown in Figures 4 and 16, the rotation of pinion 112 by the rack 92 will cause the pinion 111 to move the rack 65 with which it is engaged, on the opposite side of the shaft from the rack 92, in a downward direction. Since the rack 65 is secured to the sliding plate 58, which in turn supports the nozzle platform

140, a downward movement of the rack 65 will produce a downward movement of the nozzles and thereby remove them from the path of the subsequent rotation of the bottle platform.

5 At approximately that time when the locking of the bottles in place on the top side of the bottle platform is completed, the rack 94 in Figure 2 engages the pinion 115 for the purpose of rotating the bottle supporting platform 10 through 180°. After the completion of said rotation, the continued upward movement of said sliding member 89 engages the rack 93, in Figures 2, 4 and 16, with the pinion 112 resulting in a rotation of said pinion opposite in direction to the rotation imposed by the rack 92 since the two said racks are on opposite sides of the slot 91, and accordingly on opposite sides of the shaft 110 on which said pinion 112 is mounted. Such opposite rotation causes the rack 65, hence the member 58 and nozzle platform 140 attached thereto, to be moved in an upward direction by the pinion 111, thereby inserting the tubes 50 into the bottles and seating their open ends into the recesses of the nozzle heads, as shown in Figure 3.

20 The upward motion of the said rack 65, in which the shaft 100 is carried at its one extremity, causes said shaft to contact and raise the end 186 of the lever 183 and thereby trip the valve 180 and release a stream of cleaning fluid through the tubes 50 into the bottles as heretofore described. Such stream will continue until the shaft is caused to move downwards and disengage the lever 183.

25 At about the time the rack 93 moves the nozzles up into cleaning position, the pin 42a engages the opening 41a in the driving cam wheel 40 causing it to rotate in a clockwise rotation as appearing in Figure 15. Such rotation releases the grip of the cam mechanism 23, shown in Figure 3, on any bottles held therein and permits their removal and replacement by a new batch of bottles to be cleaned.

30 The piston rod 121 has at this point completed its upward stroke and in so doing has carried the machine through one half of a cycle and one cleaning operation.

35 To complete the cycle, the valve handle 122 is again actuated in the proper manner and the rod 121, hence the driving slide 89, begins its downward stroke, and the previously mentioned operations are carried out in reverse. First, the shaft 100 moves down away from engagement with the end 186 of the lever 183, thereby stopping the flow of cleaning fluid into the bottles. Then, the pin 42a reengages the opening 41a in the driving cam wheel 40, thereby rotating same and clamping the new batch of bottles into place. The rack 93 causes the nozzle platform to be withdrawn from the bottles as heretofore described and the rack 94 rotates the bottle holding platform back through the 180° previously rotated. This action places the new bottles into cleaning position and returns the cleaned bottles to the top of the platform. As this motion is completed the pin 42 engages the opening 41 and thereby releases the grip of the clamping mechanism 22 on the cleaned bottles and the rack 92 reengages the pinion 112, as previously described in detail, causing the nozzles to engage the open ends of the bottles to be cleaned. Such motion, as heretofore mentioned, release the flow of cleaning fluid for as long as the operator desires such flow and thus completes one cycle of the machine's operation.

40 75 This cycle may be repeated indefinitely.

It will be understood that many variations in the particular design details of this machine may be made within the scope of the invention, particularly with respect to the means for reciprocating the slide member 89, the number of bottles which a given machine may be designed to handle and the particular clamping mechanism by which the bottles are firmly held in inverted position for cleaning.

Although the machine is herein illustrated as an independent unit, it will be understood that it may be suitably associated with conveyor mechanism, both for feed and for discharge, without altering the principles of this invention.

I claim:

1. In a container cleaning machine, the combination comprising: a frame; container-supporting mechanism rotatably mounted in said frame for rotation about a horizontal axis, and means associated with said mechanism releasably holding a container in fixed position with respect to said mechanism; a nozzle and a frame supporting said nozzle for movement toward and away from the axis of rotation of said container-supporting mechanism, said nozzle supporting frame including a supporting plate slidably mounted on said first named frame; a slide reciprocable on an axis parallel to a reference line connecting said nozzle and the nearest point thereto on the line comprising the center of rotation of said container-supporting mechanism; means reacting to movement of said slide in one direction causing said supporting plate to move first in one direction parallel to the direction of movement of said slide and then in the opposite direction parallel to the direction of movement of said slide, thereby causing said nozzle first to move away from, and then toward, said container supporting mechanism when said slide is moved; means also reacting to movement of said slide in one direction rotating said container-supporting mechanism through 180°; means on said slide actuating said container holding means; manually controllable means controllably reciprocating said slide; means controllably effecting ejection of cleaning fluid from said nozzle; said parts being so associated with respect to each other that in one part of a cycle of operation of the machine a container will be held, inverted, entered by said nozzle, and contacted with cleaning fluid ejected from said nozzle, and in another part of said cycle the ejection of cleaning fluid will be terminated, the nozzle withdrawn from said container, the container returned to an upright position and released.

2. In a container cleaning machine, the combination comprising: a frame; container-supporting mechanism rotatably mounted in said frame for rotation about a horizontal axis, and means associated with said mechanism releasably holding a container in fixed position with respect to said mechanism; a nozzle and a frame supporting said nozzle for movement toward and away from the axis of rotation of said container supporting mechanism, said nozzle supporting frame including a supporting plate slidably mounted on said first named frame; a slide reciprocating on an axis parallel to a reference line connecting said nozzle and the nearest point thereto on the line comprising the center of rotation of said container-supporting mechanism; means reacting to movement of said slide in one direction means also reacting to movement of said slide in each direction rotating said container supporting mechanism through 180° with

each stroke of said slide; means on said slide actuating said container holding means; manually controllable means controllably reciprocating said slide; means controllably effecting ejection of cleaning fluid from said nozzle; means adjustably varying the positioning of the nozzle with respect to said supporting plate along a line parallel to the above-mentioned reference line; whereby in one part of a cycle of operation of the machine a container will be held, inverted, entered by said nozzle, and contacted with cleaning fluid ejected from said nozzle, and in another part of said cycle the ejection of cleaning fluid will be terminated, the nozzle withdrawn from said container, the container returned to an upright position and released.

3. In a container cleaning machine, the combination comprising: a container-holding mechanism receiving a plurality of containers on opposite sides thereof and including means releasably holding said containers fixed with respect to said mechanism; a plurality of nozzles and means supplying said nozzles with a cleaning fluid under pressure; a frame supporting said nozzles adjustably in a pattern corresponding to that of the containers held by the container-holding mechanism, which frame is supported on a pair of plates slideable toward and away from the container-holding mechanism; a nozzle driving rack carried by one of said plates; a slide mounted for reciprocation on a line substantially parallel with a reference line connecting one of said nozzles and the nearest thereto of said containers; means actuated by a fluid controllably reciprocating said slide and a source of said fluid in controllable communication with said means; a shaft rotatably mounted below said frame and having a driving pinion and a driven pinion which latter is operatively associated with the nozzle driving rack, said slide having a pair of racks thereon so associated for operation of said driving pinion by which in one portion of the stroke of said slide the said driving pinion will be rotated in one direction and the nozzles moved toward the container-holding mechanism and in another portion of the same stroke the driving pinion will be rotated in the other direction and said nozzles moved away from said container-holding mechanism, said slide also having means thereon rotating the container-holding mechanism in timed relation to the movement of said nozzles toward or away therefrom, and said slide also having means thereon operatively associated with other means on said container-holding mechanism engaging and disengaging said means releasably holding said containers; and means controllably ejecting cleaning fluid from said nozzles.

4. In a machine for cleaning containers each having an opening therein, the combination comprising: a frame; a rotatable platform having two sides mounted on said frame; means secured to said platform releasably holding at least one container on each of said sides; at least one nozzle reciprocably mounted and positioned with respect to said platform so that its reciprocable motion will carry it partially into and fully out from the opening of one of said containers in one position of said platform; means including a rack and gear effecting reciprocation of said nozzle; means supplying cleaning fluid to said nozzles and controlling the ejection of fluid therefrom; a reciprocating slide controllably and timeably actuating said rack and gear; means actuated by said slide rotating said platform in

such positional and timed relationship with the reciprocation of said nozzle that a container on one side thereof may be operatively associated with said nozzle while from the other side of said platform a container is being removed and another being put in its place; means including a piston and cylinder controllably reciprocating said slide.

5. In a machine for cleaning containers each having an opening therein, the combination comprising: a frame; a rotatable platform having two sides mounted on said frame means secured to said platform releasably holding at least one container on each of its sides; at least one nozzle positioned with respect to said platform and reciprocably mounted so that its reciprocable motion will carry it partially into and fully out from the opening of one of said containers in one position of said platform; means including a rack and gear effecting reciprocation of said nozzle; means controllably supplying cleaning fluid to said nozzles; a reciprocating slide controllably and timeably actuating said rack and gear; means actuated by said slide rotating said platform in such positional and timed relationship with the reciprocation of said nozzle that a container on one side thereof may be operatively associated with said nozzle while from the other side of said platform a container is being removed and another being put in its place; means including a piston and cylinder controllably reciprocating said slide; means also operated by said slide and associated with said platform automatically effecting gripping and releasing of said containers in timed relationship with the rotation of said platform.

6. In a container cleaning machine, the combination comprising: a frame; a container supporting mechanism mounted upon said frame for rotation about a horizontal axis; a device associated with said mechanism for releasably holding a container in fixed position with respect to said mechanism; a nozzle and a vertically reciprocable frame supporting said nozzle beneath said mechanism; a vertically reciprocable slide mounted upon said first named frame; manually controllable means controllably reciprocating said slide; means responsive to movement of said slide in one direction causing said nozzle frame to move first in one direction and then in the opposite direction, thereby causing said nozzle to move first away from and then toward said mechanism; means responsive to movement of said slide in either direction effecting rotation of said mechanism through 180°; means on said slide actuating said container holding means; whereby, in one part of a cycle of operation of the machine a container will be held, inverted, entered by a nozzle and contacted with cleaning fluid ejected from said nozzle, and in another part of said cycle ejection of cleaning fluid will be terminated, the nozzle withdrawn from said container, the container returned to an upright position and released.

7. In a container cleaning machine, the combination comprising: a frame; a container supporting mechanism mounted upon said frame for rotation about a horizontal axis; a device associated with said mechanism for releasably holding a container in fixed position with respect to said mechanism; a nozzle and a vertically re-

ciprocable frame supporting said nozzle beneath said mechanism; a vertically reciprocable slide mounted upon said first named frame; manually controllable means controllably reciprocating said slide; means responsive to movement of said slide in one direction causing said nozzle frame to move first in one direction and then in the opposite direction, thereby causing said nozzle to move first away from and then toward said mechanism; means responsive to movement of said slide in either direction effecting rotation of said mechanism through 180°; means on said slide actuating said container holding means; means connectable to a source of cleaning fluid and controllably conducting said fluid under pressure to said nozzle; whereby, in one part of a cycle of operation of the machine a container will be held inverted, entered by a nozzle and contacted with cleaning fluid ejected from said nozzle, and in another part of said cycle ejection of cleaning fluid will be terminated, the nozzle withdrawn from said container, the container returned to an upright position and released.

25. 8. In a container cleaning machine, the combination comprising: a frame; a container supporting mechanism mounted upon said frame for rotation about a horizontal axis; a device associated with said mechanism for releasably holding a container fixed position with respect to said mechanism; a nozzle and a vertically reciprocable frame supporting said nozzle beneath said mechanism; a vertically reciprocable slide mounted upon said first named frame; a source of fluid under pressure and manually controllable means responsive thereto controllably reciprocating said slide; means responsive to movement of said slide in one direction causing said nozzle frame to move first in one direction and then in the opposite direction, thereby causing said nozzle to move first away from and then toward said mechanism; means responsive to movement of said slide in either direction effecting rotation of said mechanism through 180°; means on said slide actuating said container holding means; means controllably conducting said fluid to said nozzle; whereby, in one part of a cycle of operation of the machine a container will be held inverted, entered by a nozzle and contacted with cleaning fluid ejected from said nozzle, and in another part of said cycle ejection of cleaning fluid will be terminated, the nozzle withdrawn from said container, the container returned to an upright position and released.
